UNITED STATES PATENT OFFICE.

SAMUEL DREW, OF ROCHESTER, NEW YORK.

LOCK.

No. 888,478.

Specification of Letters Patent.

Patented May 26, 1908.

Application filed August 27, 1906. Serial No. 332,140.

To all whom it may concern:

Be it known that I, SAMUEL DREW, a citizen of the United States, residing at Rochester, in the county of Monroe and State of New York, have invented a new and Improved Lock, of which the following is a specification.

The object of my invention is to provide a more efficient and economical construction for locks and more especially of that class adapted to use on outside doors.

Another object is to provide a construction permitting a maximum number of differently assorted locks and keys with a minimum change in the operating mechanism of the lock and the key.

Another object of my invention is to provide a key and a coöperating mechanism of the lock of such a character that such mechanism must be engaged at two points as far removed as consistent, by means of a key of special conformation insertible through as small an opening as possible, which opening I prefer shall be formed in a slotted and revolvable escutcheon.

Still another object of my invention is to provide an operating handle for such a lock which shall be, so far as possible, removed from the keyhole escutcheon and also as far removed as consistent from the door frame in order that the hand may not be brought into engagement with the door frame in operating the lock from the handle, which in my present invention comprises a fixed and a movable member so pivoted together that the forcible clamping together of such members operates the bolt or latch.

In carrying out my present invention, I provide a case for the internal mechanism of the lock within which a suitable bolt is arranged to slide in the usual way. I also provide mechanism under the control of a key of special construction which is adapted to hold such latch either withdrawn in its inoperative position or outwardly against withdrawal in a locking position, and the parts of such mechanism may also occupy a position permitting the operation of the latch by the operating handle. For operating my lock I also provide a key comprising two parts pivoted together, each part adapted, when in operative position within the lock, to engage a different tumbler or set of tumblers so as to permit the turning of the key and the proper movement of the parts operated thereby, such parts being locked against such move-

ment except as such tumblers are properly engaged by such key, each part of which has that peculiar conformation adapted by engagement therewith to release such tumblers, 60 and by providing for each part of the key a series of say eight or ten different conformations adapted to operate correspondingly differently conformed tumbler mechanisms, I may provide sixty-four or one hundred differently assorted locks and keys without material modifications in the general appearance of such locks and keys. For operating the latch or bolt when free and controlled only by its actuating spring, I provide, in 65 connection with a handle nearly such as applied to outside doors, and in place of the usual thumb piece for the latch, an operating member pivoted on the inside of the handle and adapted, upon grasping and clamping 70 such parts together by the hand or fingers of the operator, to operate the latch or bolt so that the door may be opened.

Although many of the features of my present invention are applicable to locks in general, I have shown them as embodied in a combined lock and latch adapted to use on an outside door and operable from the outside by means of the key at all times but by means of the handle only when the parts 80 under control of the key are in position to permit such operation by the handle. Such parts are operable also from the key in such a way as to hold the bolt either in its locked or outermost position or unlocked and inoperative in its innermost position, or again such parts may be moved by the key to permit the operation of the latch or bolt by the handle, and in this case such bolt or latch is normally held in its locking position by 85 means of its actuating spring.

The drawings are as follows:—Figure 1 shows in side view that portion of my lock arranged to be inserted in the mortise or recess therefor in a door and with the side of 100 the case thereof towards the observer removed to show the internal mechanism thereof; while Fig. 2 shows this same part of my lock, but with the case thereof complete and with the operating member J inserted in place. Fig. 3 shows in a vertical sectional view, part of the lock and the external plate carrying the escutcheon and with the operating and controlling mechanism J external to such case secured in place 105 and with the key partially inserted therein. Fig. 4 shows a portion of the edge of the door

with my lock inserted therein and with parts broken away to show the construction and operation of the handle and the key-operated mechanism and the key inserted therein and 5 also shows the knob for operating the lock from the inside of the door, and in this figure the operating handle on the outside of the door is shown in vertical section, while the similar handle on the inside of the door is 10 shown in full. Fig. 5 shows in face view the plate P for supporting and carrying the operating handle and the escutcheon of my lock. Figs. 6 and 7 are face and edge views respectively of the changeable guard section 15 seen at the lower edge of the member J. Fig. 8 is a central transverse sectional view of the handle H and the member h pivoted thereto, showing such parts as occupying the positions which they assume when the 20 latch has been operated thereby. Fig. 9 is a rear view of the element J.

Similar letters refer to similar parts throughout the several views.

Referring to the drawings,—A comprises 25 the case of my lock and A¹ the removable side plate thereof located on that side next to the observer in Fig. 2. In my lock there is slidably supported, in substantially the usual method, the combined latch and bolt L beveled, as indicated, at its outer end to permit of its operation in the well known way 30 as a latch. With the lock there is provided the usual latch or catch plate adapted to be secured to the door frame and to be engaged 35 by the latch or bolt for holding the door closed, such plate forming no part of my present invention is not shown herein. This latch L is arranged to slide out and in,— 40 from left to right and right to left, as indicated in Figs. 1 and 2, and is normally under the influence of a spring S of the usual construction, operating to force such latch to its extreme left hand position, as seen in Figs. 1 and 2. The shank of this latch L carries 45 two projections c between which the cam C may be caused to occupy a horizontal position by swinging in either direction, that is, upwardly to the left or upwardly to the right. The latch L in Fig. 1 occupies a position 50 permitting such cam C to be swung upwardly to the left without engaging the left hand projection c on the shank thereof. For this position of the cam C, that is, moved upwardly to the left as indicated in dotted 55 lines at C¹ in Fig. 1, the latch L is, as will at once be understood, forcibly held outward against withdrawal until such cam C has been moved again to the position indicated in full lines in Fig. 1. When such cam C has 60 been moved upwardly and to the right, as indicated in dotted lines at C² in Fig. 1, the latch L is forced thereby to its extreme right hand position, in which position it is firmly held by such cam C engaging the right hand 65 projection c on the latch L and against the

action of the spring S until such cam C is again moved to the position indicated in full lines in Fig. 1.

Near the right hand end of the shank of the latch L is seen a pin p³ which is engaged by the slot in the lower end of the angular lever t² pivoted at p². The upper end of this lever t² extends first horizontally to the left from the pivot p² and terminates in a rounded upward extension engaged by the lever t¹ 70 pivoted at p¹ within the case A of the lock. This lever t¹ is preferably of a width at each end nearly equaling the distance between the side plates of the lock and is engaged at its right hand end, as seen in Figs. 1 and 2, by 75 two levers h¹ pivoted as shown in Fig. 4 at p between the side flanges formed on the handle H. These levers h¹ carry each a downward extension h adapted to be moved within and between the flanges on the handle H 80 by the hand of the operator to operate the latch L, and in so operating the latch L, a member h of a lever h¹ is forced outwardly and into the member H and between the flanges thereon by clamping such handle H 85 and member h with the hand of the operator; this causes a downward movement of the inner end of the lever h¹, which engages the right hand end of the lever t¹ and forces the same downwardly, carrying with it the upper end of the lever t², forcing the lower end 90 thereof to the right, as seen in Fig. 1, and thereby moving the latch L inwardly and to the right by means of the connection already described between such lever t² and such 95 latch L. The shank of this latch L has a slot e therein, as seen in Fig. 1, adapted to receive the stem of the cam C revolvably supported in suitable openings therefor not seen 100 in the side plates of the case A of the lock. Through the square hole therefor seen in the stem of such cam C extends the square rod k² having its left hand end, as seen in Fig. 4, 105 being the end towards the inside of the door, secured within a suitable operating knob K¹, such knob revolvably supported within a depression formed therefor in the plate P, seen 110 on the inside of the door. A suitable spring is provided for holding this knob K¹ in its extreme inner position, such spring engaging 115 the plate P and the shoulder on the inner end of the knob K¹ and operating to force the rod k² to the left, as seen in Fig. 4, to bring the square portion thereof in engagement with the square recess therefor in the operating 120 member J secured upon the outside of the case of the lock and within an opening therefor in the door and on the outside thereof.

It will be readily understood that by grasping the knob K¹ and drawing the same 125 inwardly until the outer or left hand end of the rod k², as seen in Figs. 3 and 4, is out of engagement with the member J, then such knob K¹ may be turned, either over to the right or over to the left to move the cam C 130

from either one of its horizontal positions, indicated at C¹ and C² in Fig. 1. Thus it will be seen that the latch L, when held in its innermost and inoperative position or when 5 held outwardly in its locking position by means of the cam C, may be released from the inside of the door by means of the knob K¹ so as to place the latch L under the control of the latch lever h pivoted to the handle H.

10 The plate P on the outside of the door has revolvably secured therein the escutcheon I having two alined and radially extending slots therein, and through either one of which, as indicated in Figs. 3, 4 and 5, the 15 key K may be inserted. The plate A¹ comprising the side plate of the lock towards the observer as seen in Fig. 2, has secured thereon by means of screws a guideway consisting of two nearly semicircular members b and b¹ 20 each secured to the plate A¹ of the lock by means of screws and each member b carries a tongue, as seen, engaging in the groove therefor in the member J.

The revoluble member J has formed there- 25 in three slots of the character indicated in face view in Fig. 2 and in section in Figs. 3 and 4 and in rear view in Fig. 9, adapted to receive the parts k and k¹ of the key K when inserted through the upper slot therefor in 30 the revoluble escutcheon I, and for this purpose before the insertion of such key the escutcheon I is rotated until the alined slots therein occupy vertical positions, as indicated in Fig. 5.

35 The square rod k² extends normally into a square recess therefor in the revoluble element J, as seen in Figs. 3 and 4, and the knob K¹ cannot, therefore, be rotated independently of the element J except as such 40 knob K¹ is drawn to the left, as seen in Figs. 3 and 4, carrying with it such rod k² and drawing the right hand end of the same within the case A and out of the socket therefor, seen in Figs. 3 and 4, in the center of the 45 revoluble element J. Normally, therefore, the knob K¹ and the rod k² are held against rotation and therewith also the cam C except as turned with and by this revoluble element J. This element J has two peripheral grooves therein, as seen, j and j', the latter of which is in engagement with the inwardly projecting flanges on the semicircular elements b and b¹ and a similar tongue on the element b². The groove j is provided 50 to receive a guard i carried by the element b², which flange and the corresponding groove j therefor are varied in depth to meet the differently conformed keys, one feature of the difference between such keys comprising the 55 differences in conformation to meet the varying depths of the guards i. This member b² is bored, as indicated in Figs. 3, 4 and 7, to receive the tumbler pins r and r¹ and constitutes, therefore, suitable guideways for 60 such pins, which are secured respectively

upon the levers a and a¹, each pivoted in turn upon a pin p⁴ extending transversely of the lock case; and each of such levers a and a¹ is actuated by an independent spring v and v¹ respectively, within the lock case, in such a 70 way as to force upwardly the tumbler pins r and r¹, and such pins r and r¹ are carried by outwardly bent arms on the levers a and a¹ respectively extending through a suitable opening therefor in the plate A¹ of the lock. 75 These pins r and r¹ are each of a different length, as will be noted, and normally extend therefore different distances upwardly through the guard section b² and into slots formed in the element therefor 80 and also for receiving the member k¹ of the key K. Another pair of tumbler pins o and o¹ is seen secured respectively to springs s and s¹ fastened in turn, as seen in Fig. 1, on the inside of the case A of the lock. These 85 pins o and o¹ are guided in the openings therefor through the side plate of the lock and they are of different lengths and extend normally different distances into the slots in the member J adapted to receive the 90 member k of the key K. The conformation of the inner and operative end of the member k of the key K is such that when such key K is in operative position the tumbler pins o and o¹ are forced inwardly to the left, 95 as seen in Fig. 4, so as to be out of engagement with the member J to permit the rotation thereof, such member J as indicated, being conformed to fit the conformation of the inner end of the member k of the key K, 100 when such key is in position. In a similar way the pins r and r¹ extend different distances upwardly within the slots in the element J for the member k¹ of the key K, and they are forced out of such slots and beyond 105 the periphery of the element J by means of the member k¹ of the key K, to permit such member J to be revolved by the key K.

The plate A¹ of the case A carries a member b³ conformed to fit the opposing inner 110 surface of the element J, as indicated in Figs. 3 and 4, which extends for a short distance each side of the slot in such element J to receive the member k of the key K and this member b³ is slotted to receive the end 115 of the member k of the key K in order that a key K carrying an element k of improper conformation will engage within such slot in this element b³ and thereby prevent the rotation of the element J when one of the 120 pins o and o¹ has been forced outwardly by such key far enough to permit of the rotation of such element J; that is, with a key of improper conformation, either a part of the member k of such key will engage the slot in 125 the member b³ or one of such pins o and o¹ will not be forced out of engagement with the slot in the element J by the member k of the key K, in order to permit the rotation thereof. In a similar way when a key of 130

- improper conformation is used either one of the projecting fingers on the members k^1 of such key will engage within the slot in the element b^2 or one of the pins r or r^1 not be forced out of engagement with the slot in the element J. It will thus be readily understood that in operating my lock from the outside it is necessary that there be used a key K having its members k and k^1 properly conformed to engage the tumbler pins and move them far enough without at the same time engaging either the member b^3 or the member b^2 in such a way as to prevent the rotation of the element J.
- 15 The insertion of the key K in the manner already described and the rotation thereof one quarter of a revolution over to the right results in carrying the cam C upwardly to the left to a position where it holds the latch 70 L in its outermost or locking position. The key may then be withdrawn and at any time thereafter when desired the parts interior to the case of the lock may be returned to the positions indicated in full lines in Fig. 1 by 75 the operation of the knob K¹ in the manner already described, or such parts may be moved to such positions by inserting the key K in the manner already described and turning the same one quarter of a revolution over 80 to the left and again when the parts interior to the case of the lock occupy the positions indicated in full lines in Fig. 1, the insertion of the key K and turning the same over one quarter of a revolution to the left results 85 in forcing the latch L to its innermost and inoperative position where it remains after the withdrawal of the key K until the cam C has been moved to the position indicated in Fig. 1 in full lines, either by the insertion of 90 the key K and the rotation of the same one quarter of a revolution over to the right or by the operation of the knob K¹ in the manner already described. It is obvious that the latch or bolt L may be held in its operative or inoperative position by means of the cam C, and that such cam C may be moved either by the key K or the knob K¹, as desired, to either one of three positions, as follows:—first, in the position holding the latch 95 100 L forcibly outward; second, to the position shown in Fig. 1 where the latch is under the influence of the spring S and the latch-handle h, or third, to a position holding the latch L within the case A and therefore inoperative; 105 and it is also obvious that whatever the position of the cam C and no matter by what means it has been moved to such position, it may be moved to either of the two other positions therefor by means of either the key K 110 or the knob K¹. The element J, it will be noticed, is revolvably supported in proper position by the flanges on the members b and b¹ engaging the bottom of the groove j¹ therefor in the periphery of the member J, and 115 that too regardless of the diameter of the 120 125 130

outwardly extending tongues or ridges seen each side of such groove j¹. It will also be understood that the extension radially outward of each of these ridges each side of the groove j¹ in the element J will be varied in 70 the differently assorted locks to correspond with the fingers of the member k¹ of the key K, which, when such key is in operative position, are in alinement with such ridges and that such fingers on the member k¹ of the key K comprise, when such key is in position, substantially continuations of the surface of such ridges after forcing the tumbler pins r and r¹ outwardly.

The operation of my lock is believed to be 80 sufficiently clear from the above description to call for no further statement thereof.

What I claim is:—

1. In a lock, a bolt or latch; a cam adapted to occupy, as desired, a neutral or either one 85 of two operative positions, and, when moved to either one of its operative positions, to engage, move to and hold the bolt at the corresponding end of its path, and, when at its neutral position, permitting independent 90 motion of such bolt to and from each end of its path.

2. In a lock, a bolt or latch; a cam adapted to occupy, as desired, a neutral or either one 95 of two operative positions, and, when moved to either one of its operative positions, to engage, move to and hold the bolt at the corresponding end of its path, and, when at its neutral position, permitting independent motion of such bolt to and from each end of its 100 path and a movable element adapted to actuate said cam to and from each one of its three positions and having slots therein to receive the key.

3. In a lock, a bolt or latch; a cam adapted 105 to occupy, as desired, a neutral or either one of two operative positions, and, when moved to either one of its operative positions, to engage, move to and hold the bolt at the corresponding end of its path, and when at its 110 neutral position, permitting independent motion of such bolt to and from each end of its path; a movable element adapted to actuate said cam to and from each one of its three positions and having slots therein to receive 115 the key and locking means comprising two independent tumbler mechanisms each adapted to engage and hold said movable element when in any one of said positions, each tumbler mechanism adapted to be moved out of 120 engagement with the movable element only by a key member of special conformation when inserted within a slot therefor.

4. In a lock, a bolt or latch; a cam adapted 125 to occupy, as desired, a neutral or either one of two operative positions, and, when moved to either one of its operative positions, to engage, move to and hold the bolt at the corresponding end of its path, and, when at its neutral position, permitting independent 130

motion of such bolt to and from each end of its path; a movable element adapted to actuate said cam to and from each one of its three positions and having slots therein to receive the key; locking means comprising two independent tumbler mechanisms each adapted to engage and hold said movable element when in any one of said positions, each tumbler mechanism adapted to be moved out of engagement with the movable element only by a key member of special conformation when inserted within a slot therefor and a fixed stop adapted to be engaged by a key of improper conformation when inserted in a slot in said movable element to release therefrom the corresponding tumbler mechanism.

5. In a lock, a bolt or latch; a cam adapted to occupy, as desired, a neutral or either one of two operative positions, and, when moved to either one of its operative positions, to engage, move to and hold the bolt at the corresponding end of its path, and, when at its neutral position, permitting independent motion of such bolt to and from each end of its path; a movable element adapted to actuate said cam to and from each one of its three positions and having slots therein to receive the key members; locking means comprising two independent tumbler mechanisms each adapted to engage and hold said movable element when in any one of said positions, each tumbler mechanism adapted to be moved out of engagement with the movable element only by a key member of special conformation when inserted within a slot therefor; a fixed stop adapted to be engaged by a key of improper conformation when inserted in a slot in said movable element to release therefrom the corresponding tumbler mechanism.

6. In a lock, a bolt or latch; a cam adapted to occupy, as desired, a neutral or either one of two operative positions, and, when moved to either one of its operative positions, to engage, move to and hold the bolt at the corresponding end of its path, and, when at its neutral position, permitting independent motion of such bolt to and from each end of its path; a movable element adapted to actuate said cam to and from each one of its three positions and having slots therein to receive the key members; locking means comprising two independent tumbler mechanisms each adapted to engage and hold said movable element when in any one of said positions, each tumbler mechanism adapted to be moved out of engagement with the movable

element only by a key member of special conformation when inserted within a slot therefor; a fixed stop adapted to be engaged by a key of improper conformation when inserted in a slot in said movable element to release therefrom the corresponding tumbler mechanism; a key for actuating such tumbler mechanisms comprising two members each adapted to enter a corresponding slot in such movable member and release the corresponding tumbler mechanism without engaging the corresponding fixed stop, said key members pivoted together and adapted to swing on their pivotal connection while being inserted in the slots therefor and fixed stops for limiting the movement of each member of such key in actuating such tumbler mechanisms.

7. In a lock, a bolt or latch; a cam adapted to occupy, as desired, a neutral or either one of two operative positions, and, when moved to either one of its operative positions, to engage, move to and hold the bolt at the corresponding end of its path, and, when at its neutral position, permitting independent motion of such bolt to and from each end of its path and a revoluble element adapted to actuate said cam to and from each one of its three positions and having slots therein to receive the key.

8. In a lock, a bolt or latch; a cam adapted to occupy, as desired, a neutral or either one of two operative positions, and, when moved to either one of its operative positions, to engage, move to and hold the bolt at the corresponding end of its path, and when at its neutral position, permitting independent motion of such bolt to and from each end of its path; a revoluble element adapted to actuate said cam to and from each one of its three positions and having slots therein to receive the key and locking means comprising two independent tumbler mechanisms each adapted to engage and hold said revoluble element when in any one of said positions, each tumbler mechanism adapted to be moved out of engagement with the revoluble element only by a key member of special conformation when inserted within a slot therefor.

9. In a lock, a bolt or latch; a cam adapted to occupy, as desired, a neutral or either one of two operative positions, and, when moved to either one of its operative positions, to engage, move to and hold the bolt at the corresponding end of its path, and, when at its neutral position, permitting independent motion of such bolt to and from each end of its path; a revoluble element adapted to actuate said cam to and from each one of its three positions and having slots therein to receive the key; locking means comprising two independent tumbler mechanisms each adapted to engage and hold said revoluble element when in any one of said positions,

- each tumbler mechanism adapted to be moved out of engagement with the revoluble element only by a key member of special conformation when inserted within a slot therefor and a fixed stop adapted to be engaged by a key of improper conformation when inserted in a slot in said revoluble element to release therefrom the corresponding tumbler mechanism.
10. In a lock, a bolt or latch; a cam adapted to occupy, as desired, a neutral or either one of two operative positions, and, when moved to either one of its operative positions, to engage, move to and hold the bolt at the corresponding end of its path, and, when at its neutral position, permitting independent motion of such bolt to and from each end of its path; a revoluble element adapted to actuate said cam to and from each one of its three positions and having slots therein to receive the key members; locking means comprising two independent tumbler mechanisms each adapted to engage and hold said revoluble element when in any one of said positions, each tumbler mechanism adapted to be moved out of engagement with the movable element only by a key member of special conformation when inserted within a slot therefor; a fixed stop adapted to be engaged by a key of improper conformation when inserted in a slot in said revoluble element to release therefrom the corresponding tumbler mechanism and a key for actuating such tumbler mechanisms comprising two members each adapted to enter a corresponding slot in such revoluble element and release the corresponding tumbler mechanism without engaging the corresponding fixed stop, said key members pivoted together and adapted to swing on their pivotal connection while being inserted in the slots therefor.
11. In a lock, a bolt or latch; a cam adapted to occupy, as desired, a neutral or either one of two operative positions, and, when moved to either one of its operative positions, to engage, move to and hold the bolt at the corresponding end of its path, and, when at its neutral position, permitting independent motion of such bolt to and from each end of its path; a revoluble element adapted to actuate said cam to and from each one of its three positions and having slots therein to receive the key members; locking means comprising two independent tumbler mechanisms each adapted to engage and hold said revoluble element when in any one of said positions, each tumbler mechanism adapted to be moved out of engagement with the revoluble element only by a key member of special conformation when inserted within a slot therefor; a fixed stop adapted to be engaged by a key of improper conformation when inserted in a slot in said revoluble element to release therefrom the corresponding tumbler mechanism; a key for actuating such tumbler mechanisms comprising two members each adapted to enter a corresponding slot in such revoluble element and release the corresponding tumbler mechanism without engaging the corresponding fixed stop, said key members pivoted together and adapted to swing on their pivotal connection while being inserted in the slots therefor and fixed stops for limiting the movement of each member of such key in actuating such tumbler mechanisms.
12. In a lock; a movable element having slots therein to receive the key members; locking means comprising two independent tumbler mechanisms each adapted to engage and hold said movable element, each tumbler mechanism adapted to be moved out of engagement with the movable element only by a key member of special conformation when inserted within a slot therefor; a fixed stop adapted to be engaged by a key of improper conformation when inserted in a slot in said movable element to release therefrom the corresponding tumbler mechanism, and a key for actuating such tumbler mechanisms comprising two members each adapted to enter a corresponding slot in such movable member and release the corresponding tumbler mechanism without engaging the corresponding fixed stop, said key members pivoted together and adapted to swing on their pivotal connection while being inserted in the slots therefor.
13. In a lock; a movable element having slots therein to receive the key members; locking means comprising two independent tumbler mechanisms each adapted to engage and hold said movable element, each tumbler mechanism adapted to be moved out of engagement with the movable element only by a key member of special conformation when inserted within a slot therefor; a fixed stop adapted to be engaged by a key of improper conformation when inserted in a slot in said movable element to release therefrom the corresponding tumbler mechanism; a key for actuating such tumbler mechanisms comprising two members each adapted to enter a corresponding slot in such movable member and release the corresponding tumbler mechanism without engaging the corresponding fixed stop, said key members pivoted together and adapted to swing on their pivotal connection while being inserted in the slots therefor and fixed stops for limiting the movement of each member of such key in actuating such tumbler mechanisms.
14. In a lock; a revoluble element having slots therein to receive the key members; locking means comprising two independent tumbler mechanisms each adapted to engage and hold said revoluble element, each tumbler mechanism adapted to be moved out of engagement with the revoluble element only

by a key member of special conformation when inserted within a slot therefor; a fixed stop adapted to be engaged by a key of improper conformation when inserted in a slot 5 in said revoluble element to release therefrom the corresponding tumbler mechanism and a key for actuating such tumbler mechanisms comprising two members each adapted to enter a corresponding slot in such revoluble member and release the corresponding tumbler mechanism without engaging the corresponding fixed stop, said key members 10 pivoted together and adapted to swing on their pivotal connection while being inserted 15 in the slot therefor.

15. In a lock; a revoluble element having slots therein to receive the key members; locking means comprising two independent tumbler mechanisms each adapted to engage and hold said revoluble element, each tumbler mechanism adapted to be moved out of engagement with the revoluble element only by a key member of special conformation when inserted within a slot therefor; a 20 fixed stop adapted to be engaged by a key of improper conformation when inserted in a slot in said revoluble element to release there- 25

from the corresponding tumbler mechanism; a key for actuating such tumbler mechanisms; comprising two members each adapted to enter a corresponding slot in such revoluble member and release the corresponding tumbler mechanism without engaging the corresponding fixed stop, said key members 30 pivoted together and adapted to swing on their pivotal connection while being inserted in the slots therefor and fixed stops for limiting the movement of each member of such key in actuating such tumbler mechanisms.

16. In a lock; two independent tumbler 40 mechanisms and a key comprising two pivotally connected members each adapted to operate one of such tumbler mechanisms.

17. In a lock; two independent tumbler 45 mechanisms and a key comprising two pivotally connected members each adapted to swing upon their pivotal connection when engaging and operating such tumbler mechanisms.
